UNITED STATES PATENT OFFICE.

THOMAS C. BROWN, OF WEST ORANGE, NEW JERSEY, ASSIGNOR TO NEW JERSEY PATENT COMPANY, OF WEST ORANGE, NEW JERSEY, A CORPORATION OF NEW JERSEY.

SYSTEM FOR HANDLING CORRESPONDENCE.

1,359,959.

Specification of Letters Patent. Patented Nov. 23, 1920.

Application filed October 14, 1916. Serial No. 125,564.

To all whom it may concern:

Be it known that I, THOMAS C. BROWN, a citizen of the United States, and a resident of West Orange, in the county of Essex and 5 State of New Jersey, have invented a certain new and useful System for Handling Correspondence, of which the following is a description.

My invention relates to a system for handling correspondence, and more particularly to an improved method and means for facilitating the handling of a dictated phonograph record, together with the correspondence and other papers which relate to said 10 record, as when the same is to be sent from one person to another, for example, from a dictator to the transcriber and vice versa.

A satisfactory arrangement or system for transporting a dictated phonograph record, 20 together with the correspondence and other papers relating to said record, has heretofore been a feature lacking in the application of voice writing in many business offices. Various systems have been resorted to for this purpose, such as the securing of 25 the correspondence and other papers to the record carton by wrapping the same about such carton and by rolling the papers into a roll and then stuffing the same into the 30 record or the end of the record itself. These systems or arrangements, however, are objectionable for the reason that the cartons, together with the records therein and the 35 papers attached thereto, are unwieldy to handle and the papers become so curled and mussed as to render them difficult to file. Moreover, with these arrangements the 40 finished work is seldom returned to the dictator by the transcriber in a neat and clean condition.

In another system heretofore used, an ordinary correspondence folder has been employed to transport the correspondence and papers relating to the dictated record. With 45 this scheme, however, the folder is identified with the particular record, to which the papers contained in such folder relate, by writing both the number of the carton for the dictated record and the dictator's name 50 or initials upon the folder, and also upon the usual memorandum or index made by the dictator when dictating the record that is sent in the carton to the transcriber. It 55 will be apparent that this scheme is objectionable in that it involves quite a num-

ber of operations on the part of the dictator. Moreover, when the folder containing the papers is returned and it is desired to employ the same folder with another record, or to transfer the same to another dictator 60 for his use, it is necessary either to erase or cross out the carton number or the dictator's name, or both, on the folder and to write the number of the carton for the new record or the other dictator's name or both thereon. 65 Accordingly, the folder after a short time is in a very bad condition and its life is comparatively limited.

Still another system heretofore used and employing the folders is as follows: A permanent number is applied to the folder itself and no number to the record carton, and the name of the dictator is written or printed on the folder. In using such a folder, in order to identify the record carton with the 75 folder, the dictator performs the following operations:—

1. He dictates his name at the beginning of the record.
2. He dictates the number of the folder 80 given with the record.
3. He writes the number of the folder on the dictation memorandum or index.
4. He writes his name or initials on the 85 dictation memorandum or index.

This scheme in addition to involving a considerable number of operations on the part of the dictator is also seriously objectionable, especially in a busy transcribing department, as it is frequently impracticable 90 to visually identify the record and the folder, one with the other, which renders it necessary to first listen to the record in order to ascertain the dictator's name and the number of the correspondence folder, and to 95 then search among the papers in the transcribing department for the folder bearing the number.

The principal objects of my invention are to provide an improved method wherein the 100 above objections will be largely obviated and improved means for use in carrying out such method. My improved method preferably consists in employing a container, such as a folder, for the correspondence and other 105 papers relating to a dictated record, placing the dictated record in a numbered carton, writing only the number of the record carton on the usual memorandum or index made by the dictator during the dictating 110

of the record, applying said memorandum to the correspondence container so that the record carton number thereon will be visible preferably from outside the container, and then sending the carton together with the container and contents to the desired point. A novel container is employed in carrying out my method, which is preferably adapted to hold the memorandum or index in such a position that the carton number written thereon will be visible preferably from outside the container.

Other objects and features of my invention will be hereinafter more fully described and claimed.

In order that my invention may be more fully understood, attention is directed to the drawing accompanying and forming a part of this specification, in the several views of which like parts are designated by the same reference characters, and in which:

Figure 1 is a plan view of a novel correspondence folder employed in carrying out my invention;

Fig. 2 is a fragmentary plan view of the folder shown in Fig. 1, showing the memorandum and name card disposed in the respective pockets therefor in the folder;

Fig. 3 is a fragmentary plan view of a folder such as shown in Fig. 1 provided with modified means for holding the memorandum or index; and

Fig. 4 is an enlarged cross sectional view on line 4-4 of Fig. 3.

Referring to the drawing and especially to Figs. 1 and 2, reference character 1 represents a container, here shown as a folder, for correspondence or like matter. The folder 1 comprises a front leaf 2 and a rear leaf 3 connected at the fold 4. The front leaf 2 of the container or folder 1 is provided with suitable means for removably holding the usual memorandum or index made by a dictator while dictating a record, in such a position that a portion of the index will be visible preferably from outside the container. In the preferred form of folder, means is also provided for removably holding a name card so that a portion thereof will be visible preferably from outside the container to disclose the name of the dictator. As shown in Figs. 1 and 2, the means for holding the memorandum and name card consists of a pair of pockets 5 and 6 provided on the front leaf 2 of the folder, substantially centrally thereof, the front wall of the pocket 5 being provided with an opening or window 7 and the front wall of the pocket 6 being provided with an opening or window 8. The pockets 5 and 6 are preferably formed by securing a substantially rectangular strip 9 at its side edges, one end, and intermediate its ends, between the windows or openings 7 and 8, to the leaf 2. Spaces are preferably provided on either

side of the strip 9 for written instructions to dictators and transcribers. Suitable instructions are also printed or written on the face of the folder preferably at the left of the window or opening 8 for the return of the transcribed matter and the related papers to the dictator. Other instructions or the like may also be printed or written on the face of the folder.

The use of the folder above described is as follows:—When the dictator has finished dictating a record, he writes the number appearing on the carton for the dictated record on the tab end of the usual memorandum or index 10. He then places the record in the numbered carton and inserts the memorandum or index 10 into the pocket 5 through the opening or window 7 in such a manner as to leave the tab end of the index with the record carton number thereon exposed at the opening 7 as shown in Fig. 2. In accordance with the instructions visible on the back of a name card 11, disposed in the pocket 6, through the opening or window 8 in the front wall of pocket 6, the dictator then removes the name card 11 from the pocket 6, turns the card over, and after inserting the card into the pocket 6, writes his name thereon through the opening 8. The dictator then sends the folder 1, together with the carton and the record therein, to the transcriber. When the transcriber has finished the transcript of the record, the same is placed in the folder together with the related papers and returned to the dictator in accordance with instructions appearing upon the face of leaf 2.

By reason of the use of the interchangeable name card 11, which may be of celluloid or other suitable material, the folder 1 may be transferred in good condition from one dictator to another for use, it being merely necessary to erase the name of one dictator on the card 11 and to write the name of the other dictator thereon or to substitute a new name card therefor.

The use of this folder is also advantageous in that the danger of losing the celluloid memorandum slip 10 or other index when placed in the pocket 5 of the folder is much less than when merely placed in the inside of the record carton and then carried to the transcriber as has heretofore been customary.

As a matter of convenience, it is preferable to represent the memorandum or index on the face of the strip 9, as shown at 12 in Fig. 1, and to provide spaces on either side of such representation for suitable indexing instructions.

It is obvious that other means may be employed for removably holding the memorandum or index 10 on the folder or container 1 in such a position that the carton

number thereon will be visible. For example, as shown in Figs. 3 and 4, a pair of aligned spring clips or fingers 14, suitably secured to the front leaf 2 of the folder 1 as by means of fastening eyes 15, may be used for this purpose.

While I have described the preferred embodiments of my invention, it is to be understood that various modifications may be made therein without any departure from the spirit of the invention and the scope of the appended claims.

Having now described my invention, what I claim and desire to protect by Letters Patent of the United States is as follows:—

- 15 1. A container for correspondence or the like, and a substantially rectangular strip secured at two sides, one end and transversely thereof intermediate its ends to one wall of the container, whereby a pair of pockets are formed by said strip and said wall of the container, one side of each of said pockets being provided with a window or opening, substantially as described.
- 20 25 2. A container for correspondence or the like, and a substantially rectangular strip secured at two sides, one end and transversely thereof intermediate its ends to one wall of the container whereby a pair of pockets are formed by said strip and said wall of the container, each portion of the

strip forming one side of each of said pockets being provided with a window or opening, substantially as described.

3. The combination of a container for correspondence relating to matter on a photograph record tablet, an instruction or correction slip for use in connection with such record tablet, and a card with the name of the dictator, said container being provided with separate means for respectively holding said slip and card in a position with a portion of each visible, substantially as described.

4. The combination of a container for correspondence relating to matter on a photograph record tablet, an instruction or correction slip for use in connection with such record tablet, and a card with the name of the dictator, said container being provided with a pair of pockets for respectively holding said slip and card, each of said pockets being provided with an opening or window whereby a portion of the slip and card will be visible when disposed in such pockets, substantially as described.

This specification signed and witnessed this 6th day of October, 1916.

THOMAS C. BROWN.
